REVERSIBLE AIR CONDITIONING SYSTEM WITH HOT GAS DEFROSTING MEANS

David Goldenberg, Trenton, N. J., assignor to Kramer Trenton Company, Trenton, N. J., a corporation of New Jersey

Application November 5, 1954, Serial No. 467,115

10 Claims. (Cl. 62—161)

This invention relates to a reversible air conditioning system with hot gas defrosting means and has for an object to provide such a system which includes indoor and outdoor coils and in which the outdoor coil can be defrosted during cold weather without the necessity of chilling the indoor space served by the indoor coil.

Another object is to provide such a system in which is positioned heat storage means that is warmed during both the cooling cycle and heating cycle (i. e., warm weather and cold weather) of the system and supplies heat for aiding in the reevaporation of the refrigerant that has been condensed in the outdoor coil during its defrosting and is returning to the compressor.

Another object is to provide such a system in which the heat storage means is small and compact, and embodies a coil, or the like, which is immersed in liquid that may freeze during defrosting cycles to give up its heat of fusion to the condensed refrigerant flowing through the said coil and, in turn, may melt during the heating cycles which follow.

Another object is to provide such a system in which the changes from cooling cycle to heating cycle, and vice-versa, as well as the occurrence and duration of defrosting cycles, are governed by the operation of a suitable flow control device, such as a 4-way valve.

Another object is to provide such a system which embodies means for obviating friction pressure drop of the refrigerant returning to the compressor during defrosting cycles due to passage through the indoor coil.

Another object is to provide such a system in which the last named means comprises a by-pass construction that also eliminates the requirement for certain control valves and piping.

A further object is to provide certain improvements in the form, construction, and arrangement of the several parts whereby the above named and other objects inherent in the invention may be effectively attained.

In brief summary, the invention comprehends an air conditioning system for buildings, which system includes both indoor and outdoor coils, or the like, that serve reversibly as evaporator and condenser for cooling the building interior in warm weather and warming it in cold weather; the outdoor coil being exposed to atmosphere. A characteristic of the system is the provision of heat storage means which accumulates heat during both the cooling and heating cycles of the system, whereby the outdoor evaporator can be defrosted by hot gas from the compressor and the resultant condensed refrigerant be reevaporated before it returns to the compressor. A modification involves the presence of means for bypassing the indoor evaporator during defrosting cycles to reduce friction pressure drop in the refrigerant flowing to the compressor.

Practical embodiments of the invention are shown in the accompanying drawing, in which,

Fig. 1 represents a diagrammatic layout of the system; and

2

Fig. 2 represents a similar view of a modified form.

Referring to Fig. 1, the compressor is denoted by 1, and may be of any suitable type, hermetically sealed or otherwise. Its discharge conduit 2 is in communication with one port of a 4-way reversing valve 3; which is not deemed to require structural illustration or description in view of the fact that its characteristics are well understood by engineers in this field and such valves are obtainable in the open market, e. g., the product of Alco Valve Company, St. Louis, Mo. A second port of the valve is connected by a conduit 4 with the compressor intake; a third port is connected by a conduit 5 with the indoor coil 6; and the fourth port is connected by a conduit 7 with the outdoor coil 8. The arrangement of the valve ports is such that, in one position of the valve, the compressor discharge communicates with the outdoor coil and the compressor intake communicates with the indoor coil, while, in another valve position, the said communications are reversed.

10 The indoor coil 6 is fitted with the usual fan and motor, marked 9 collectively, and the same is true of the outdoor coil 8, where the fan and motor are denoted by 10. The said coils may be of conventional, or any appropriate, form and construction, adapted to serve as evaporators and also as condensers according to the refrigerant flow setting of the system; and the fan motors should be controlled by some means, preferably automatic, for causing the fans to rotate or remain idle according to the then cycle of operation of the system, all as is so well understood by engineers in this field as to call for neither illustration nor further description.

30 The outdoor coil 8 is also connected by a conduit 11, in which is positioned a suitable check valve 12, with the receiver 13, for the flow of refrigerant to the receiver when the system is operating on one cycle; and a bridging tube 14, fitted with an appropriate pressure reducing device, such as a thermostatic expansion valve 15, connects with conduit 11 at two points for the flow of refrigerant from the receiver to coil 8 when the system is operating on another cycle. The valve 15 is controlled by the usual feeler bulb 16.

40 A conduit 17 connects the receiver 13, through a solenoid valve 18, with a reevaporator which is preferably similar to that disclosed in U. S. patent application Serial No. 388,587, filed by Israel Kramer on October 27, 1953, now Patent No. 2,718,764, issued September 27, 1955. This may be briefly described as consisting of a container or tank 19, conveniently rectangular in shape and composed of steel or other proper material, which is filled with a freezable liquid, such as water, generally without any freeze depressant, such as denatured alcohol. In container 19 is located a coil 20 of any desired form, manifolded or otherwise. One end of coil 20 connects with conduit 17, and the other end with a conduit 21 that leads, through a pressure reducing device, such as a thermostatic expansion valve 22, to the indoor coil 6. Valve 22 is controlled by feeler bulb 23. A by-pass conduit 24 bridges solenoid valve 18, and a restrictor, such as a hold back valve 25, is located in the by-pass. A pair of by-pass conduits, 26 and 27, bridge expansion valve 22. In by-pass 26 are positioned a solenoid valve 28 and a check valve 29, which latter permits flow toward reevaporator 19, 20. In by-pass 27 are positioned a solenoid valve 30 and a check valve 31, the latter permitting flow toward the indoor coil 6. The points at which conduits 17 and 21 enter container 19 are suitably sealed for liquid tightness, as by stuffing boxes.

50 70 For operation on the cooling cycle, the 4-way valve 3 is set to open communication between the discharge of compressor 1 and the outdoor coil 8 through conduits 2

and 7, while the solenoid valve 18 is open and solenoid valves 28 and 30 are closed. The hot refrigerant gas now flows from the compressor to the outdoor coil 8 which functions as a condenser to liquefy the gas which passes through conduit 11 and check valve 12 to be deposited in receiver 13. From the latter the refrigerant travels through conduit 17, solenoid valve 18, coil 20, conduit 21, and expansion valve 22, to indoor coil 6, which latter now serves as an evaporator to cool the surrounding air which is circulated by fan 9. From the indoor coil, the vaporized refrigerant traverses conduit 5, the 4-way valve 3, and conduit 4 to the compressor intake for re-compression and re-circulation as just described. During this cooling cycle, the warm refrigerant imparts heat to the liquid within container 19, but the coil 20 does not function as a reevaporator.

When, as the result of seasonal change or for any other reason, it is desired to reverse the system to its heating cycle and thus warm the building enclosure in which the indoor coil 6 is located, the 4-way valve is turned to connect the discharge of compressor 1 with the indoor coil through conduits 2 and 5, while the compressor intake is connected with the outdoor coil 8 through conduits 4 and 7. Solenoid valve 18 is left open, solenoid valve 30 is left closed, and solenoid valve 28 is opened. The hot refrigerant gas now flows to the indoor coil 6, which functions as a condenser, and its fan 9 circulates the surrounding air which is warmed by the coil. The condensed refrigerant moves from the indoor coil through by-pass 26, solenoid valve 28, check valve 29, conduit 21, coil 20, conduit 17, and solenoid valve 18, to the receiver 13. From the latter the flow is through tube 14 to expansion valve 15 which lowers the pressure, and to the outdoor coil where evaporation takes place due to heat obtained from the ambient air blown over the coil by its fan. The vaporized refrigerant thence proceeds through conduits 7 and 4 to the compressor intake for re-compression and re-circulation.

When operating on the heating cycle just explained, the outdoor coil accumulates frost, especially when the temperature drops to, say, 40° F. or lower, and efficient performance calls for defrosting at appropriate intervals. This has heretofore been accomplished in systems of this general type by intermittent reversing to the cooling cycles in which heat is abstracted from the indoor air and hot gas is fed to the outdoor coil. This procedure, however, chills the indoor space and establishes an uncomfortable, if not intolerable, condition therein. To offset this, resort has been had to the provision of electric heating means for the indoor space, operative during defrosting, which, of course, not only complicates the set-up, but likewise adds materially to first cost and maintenance expense, including electrical demand charges. The present invention eliminates the just recited disadvantages by embodying defrosting means that comes into action in an operating cycle differing from both the cooling and heating cycles, as will now be described.

To initiate a defrosting cycle, the 4-way valve 3 is turned from its setting for the heating cycle, to its setting for the cooling cycle, solenoid valve 18 is closed, solenoid valve 30 is opened, and solenoid valve 28 is closed. The hot gas from the discharge of compressor 1 now flows directly to the outdoor coil 8 and melts the frost thereon. In accomplishing this, the gas is condensed and passes in liquid phase through conduit 11 and check valve 12 into the receiver 13. From the latter the flow is through conduit 17 and by-pass 24 to hold back valve 25. This valve is adjusted or set to discharge the refrigerant at low temperature, e. g. 20° F. or lower, and it thus serves as an expansion valve functioning to reduce the high temperature, high pressure liquid refrigerant into a low temperature, low pressure mixture of liquid and gas or vapor. The refrigerant in this form passes along to the coil 20 which now becomes a reevaporator with the low temperature of the refrigerant freezing the warm water

in container or tank 19 and its liquid portion being in turn, vaporized by the latent heat of fusion. In this gaseous phase the refrigerant travels through conduit 21, by-pass 27, check valve 31, solenoid valve 30, to the indoor coil 6. As the flow is in vapor phase it passes through coil 6 without evaporation and, hence, does not appreciably affect the air temperature of the enclosure within which the said coil is located. The cycle is completed by passage of the low pressure gas through conduit 5, the 4-way valve 3, and the conduit 4 to the compressor intake. During defrosting the fan 10 associated with the outdoor coil is idle, and the fan 9 associated with the indoor coil may be either idle or running.

Following completion of defrosting the outdoor coil, the system may be returned to the heating cycle by turning the 4-way valve so that the compressor discharge is connected with the indoor coil and its intake is connected with the outdoor coil, opening solenoid valve 18, closing solenoid valve 30, and opening solenoid valve 28. The indoor coil never requires defrosting because, even on the cooling cycle, the refrigerant temperature therewithin is above the freezing point.

The solenoid valves 18, 28, 30, as well as the motors for fans 9 and 10, may be automatically operated by any suitable electrical control system, with which engineers skilled in this field are so familiar as to require neither illustration nor description. Thus, for example, the defrosting cycle may be initiated and its duration determined by an electrical timer or by a pressure switch responsive to pressure at the intake of the compressor. If a timer is used, it may be held out of operation by a thermostat responsive to ambient air temperature at the outdoor coil so that it will not be effective until there is a fall to, say, 50° F. or lower. It is usually satisfactory to have manual control for the 4-way valve to reverse from cooling cycle to heating cycle, and vice versa, but it should be automatically controlled along with the solenoid valves and fan motors in connection with defrosting cycles by any appropriate electrical arrangement such, for instance, as that supplied with the above mentioned Alco valve.

The modified form of the invention represented in Fig. 2, is the same as that shown in Fig. 1, with the exceptions that by-pass 27 and its solenoid valve 30 and check valve 31, are omitted, as well as solenoid valve 28, and an indoor coil by-pass conduit is inserted in the system. The said by-pass conduit is denoted by 32, and in it are positioned a solenoid valve 33 with a check valve 34; the conduit itself spanning the indoor coil 6 and being connected with conduits 21 and 5.

This modification is useful only in the defrosting cycles. During the other two cycles (cooling and heating), the solenoid valve 33 is closed and the system operates exactly as already described when explaining the form of Fig. 1. When a defrosting cycle is initiated, valve 33 opens, valve 18 closes, and the system functions to defrost the outdoor coil as set forth in connection with Fig. 1. However, in the modified form, the reevaporated gaseous refrigerant flowing from the reevaporator 19, 20, travels through conduit 21 into the by-pass 32 and through valves 34 and 33 to conduit 5. This eliminates friction pressure drop occasioned by passage through the indoor coil 6 and hence maintains higher operating efficiency of the compressor by supplying the refrigerant to its intake at a pressure higher than would be the case if its course of travel included the indoor coil. Further, as above indicated, there is an appreciable economy derived from the fact that this modification eliminates two solenoid valves, 28 and 30, while adding only one, 33. It is also possible to simplify the design and reduce the cost of the indoor coil when the by-pass 32 is included in the system. Solenoid valve 33 may be involved in the electrical control hereinabove described.

With reference to both forms of the invention, it is preferable to have the container or tank 19 permanently filled with water, but, if desired for any reason, it could

be connected to a source of water supply and be provided with a drain. In such an arrangement, the container will be filled with warm water for the defrosting cycles, and the subsequent melt from the ice encrustation on the coil 20 be drained off. Needless to say, such a provision would be less practicable and more costly than the permanent filling of the container or tank.

Again referring to both forms of the invention, it will be clear that provision is made not only for indoor temperature conditioning at all seasons of the year and in differing climatic zones, but also for efficient defrosting of the outdoor coil without material effect upon the indoor temperature, and without requiring the presence of temporary auxiliary heating means for the indoor space.

It will be understood that various changes may be resorted to in the form, construction, and arrangement of the several parts of the system without departing from the spirit or scope of the invention; and, hence, I do not intend to be limited to details herein shown or described except as the same may be included in the claims or be required by disclosures of the prior art.

What I claim is:

1. A system of the character described including a refrigerant compressor having its discharge and intake connected by conduits with indoor and outdoor coils or the like, said system comprising, reversible refrigerant flow controlling means positioned in the conduits between the compressor and the indoor and outdoor coils for causing the indoor coil to function as an evaporator in cooling cycles of the system and to function as a condenser in heating cycles of the system and causing the outdoor coil to function as a condenser in cooling cycles of the system and to function as an evaporator in heating cycles of the system, said flow controlling means being also adapted for causing hot gas flow from the compressor discharge to the outdoor coil for defrosting the latter without causing the indoor coil to function either as an evaporator or a condenser, means positioned between the indoor and outdoor coils and in heat exchange relation with conduits connecting both said coils for storing heat during both the cooling and heating cycles of the system, and means conduit connected between the indoor and outdoor coils for refrigerant flow from the latter to the former for reevaporating refrigerant that has been condensed in the outdoor coil during defrosting.

2. A system of the character described including a refrigerant compressor having its discharge and intake connected by conduits with indoor and outdoor coils or the like, said system comprising, reversible refrigerant flow controlling means positioned in the conduits between the compressor and the indoor and outdoor coils for causing the indoor coil to function as an evaporator in cooling cycles of the system and to function as a condenser in heating cycles of the system and causing the outdoor coil to function as a condenser in cooling cycles of the system and to function as an evaporator in heating cycles of the system, said flow controlling means being also adapted for causing hot gas flow from the compressor discharge to the outdoor coil for defrosting the latter without causing the indoor coil to function either as an evaporator or a condenser.

3. A system of the character described including a refrigerant compressor having its discharge and intake connected by conduits with indoor and outdoor coils or the like, said system comprising, reversible refrigerant flow controlling means positioned in the conduits between the compressor and the indoor and outdoor coils for causing the indoor coil to function in both cooling and heating cycles of the system, said flow controlling means being also adapted for causing hot gas flow from the compressor discharge to the outdoor coil for defrosting the latter, a receiver connected by refrigerant flow conduits with the indoor and outdoor coils, a reevaporator

positioned in the conduit connecting the receiver with the indoor coil for reevaporating refrigerant condensed in the outdoor coil during defrosting and flowing toward the indoor coil, and a pressure reducing device interposed between and connected by refrigerant flow conduits with the receiver and reevaporator for cooperative functioning with the latter during defrosting.

4. A system as defined in claim 3, which also comprises a shut-off valve positioned in the conduit between the receiver and the reevaporator and a by-pass conduit spanning said valve, and in which the pressure reducing device is positioned in said by-pass conduit.

5. A system of the character described including a refrigerant compressor having its discharge and intake connected by conduits with indoor and outdoor coils or the like, said system comprising, reversible refrigerant flow controlling means positioned in the conduits between the compressor and the indoor and outdoor coils for causing the indoor coil to function in both cooling and heating cycles of the system, said flow controlling means being also adapted for causing hot gas flow from the compressor discharge to the outdoor coil for defrosting the latter, a receiver connected by refrigerant flow conduits with the indoor and outdoor coils, a reevaporator positioned in the conduit connecting the receiver with the indoor coil for reevaporating refrigerant condensed in the outdoor coil during defrosting and flowing toward the indoor coil, and heat storage means combined with the reevaporator and arranged to be warmed during the cooling and heating cycles of the system.

6. A system as defined in claim 5, in which the heat storage means is in heat exchange relation with the conduit between the receiver and the indoor coil.

7. A system as defined in claim 6, in which the reevaporator embodies a container and a coil therewithin, and in which the heat storage means is a freezable liquid in the container contacting the coil.

8. A system of the character described including a refrigerant compressor, indoor and outdoor coils or the like connected by conduits with the compressor discharge and intake, a receiver positioned between said indoor and outdoor coils, reevaporating means positioned between the receiver and the indoor coil, and reversible refrigerant flow controlling means positioned in the conduits between the compressor discharge and intake and the indoor and outdoor coils, said system embodying means for causing the indoor coil to function as both a cooling and a heating unit and for defrosting the outdoor coil, said last named means comprising, two conduits interconnecting the outdoor coil and the receiver one equipped with means permitting flow toward the receiver but inhibiting reverse flow and the other equipped with pressure reducing means operative when flow is toward the outdoor coil, two conduits interconnecting the receiver and the reevaporating means one equipped with means to close flow therethrough and the other equipped with flow restricting means operative when flow is toward the reevaporating means, three conduits interconnecting the reevaporating means and the indoor coil two equipped with means to close flow therethrough and one of the said two also equipped with means permitting flow toward the indoor coil but inhibiting reverse flow while the other of said two is also equipped with means permitting flow toward the reevaporating means but inhibiting reverse flow and the third said conduit being equipped with pressure reducing means operative when flow is toward the indoor coil.

9. A system as defined in claim 8, in which heat storage means is combined with the reevaporating means and is warmed by the circulating of refrigerant when the indoor coil is functioning as a cooling unit and also when the latter is functioning as a heating unit.

10. A system of the character described including a refrigerant compressor, indoor and outdoor coils or the like connected by conduits with the compressor discharge and intake, a receiver positioned between said indoor and out-

door coils, reevaporating means positioned between the receiver and the indoor coil, and reversible refrigerant flow controlling means positioned in the conduits between the compressor discharge and intake and the indoor and outdoor coils, said system embodying means for causing the indoor coil to function as both a cooling and a heating unit and for defrosting the outdoor coil, said last named means comprising, two conduits interconnecting the outdoor coil and the receiver one equipped with means permitting flow toward the receiver but inhibiting reverse flow and the other equipped with pressure reducing means operative when flow is toward the outdoor coil, two conduits interconnecting the receiver and the reevaporating means one equipped with means to close flow therethrough and the other equipped with flow restricting means operative when flow is toward the reevaporating means, two conduits interconnecting the reevaporating means and the indoor coil one equipped with means permitting flow toward the reevaporating means but inhibiting reverse flow and the other equipped with pressure reducing means operative when flow is toward the indoor coil, and a third conduit connecting the conduit between

the reevaporating means and the indoor coil at a point between the reevaporating means and the last named pressure reducing means with the conduit between the indoor coil and the compressor at a point between the indoor coil and the flow controlling means, said third conduit being equipped with means to close flow therethrough and with means permitting flow toward the flow controlling means but inhibiting flow in the opposite direction.
